UNITED STATES PATENT OFFICE.

CHARLES H. TOWER, OF CLEVELAND, OHIO, ASSIGNOR, BY MESNE ASSIGNMENTS, TO SPLITDORF-BETHLEHEM ELECTRICAL COMPANY, OF NEWARK, NEW JERSEY, A CORPORATION OF NEW JERSEY.

MAGNETO.

Application filed June 19, 1920. Serial No. 390,207.

The invention relates to ignition generators and is especially applicable to magneto generators of the inductor type, although the improvements are by no means limited 5 to that type of generators.

The invention has for its principal objects: (a) the reduction of the cost of producing ignition generators, (b) the reduction of the size and weight of such generators, (c) the increase of the efficiency of 10 ignition generators, and (d) a construction permitting easy assembly and disassembly of the parts.

Other objects, more or less ancillary to 15 the above, as well as the manner in which all of the objects are attained, will be pointed out in the following discussion and accompanying drawings.

In the drawings, Fig. 1 is a central vertical section through an inductor type, high tension generator embodying my improvements.

Fig. 2 is a section on the line 2—2, Fig. 1.

Fig. 3 is a right end elevation of the 25 generator, part of the breaker casing being broken away.

Fig. 4 is a section on the line 4—4, Fig. 1.

Fig. 5 is a section on the line 5—5, Fig. 1.

Fig. 6 is a section on the line 6—6, Fig. 2.

Referring in detail to the construction 30 illustrated, (1) indicates in its entirety a stator frame structure integrally cast of non-magnetic metal. This frame may be cast in any suitable manner and of any suitable 35 non-magnetic metal, but I prefer to die-cast it and to use a suitable aluminum alloy to reduce the weight of the structure as much as possible. The frame (1) comprises a base part (1^a), end walls (1^b) and (1^c) and 40 side walls (1^d) and (1^e).

In the base part of the frame (1) is an iron pole piece (2) formed with a polar surface (2^a). The pole piece (2) serves also as a portion of the base of the generator, being 45 preferably formed with tapped holes (2^b) to receive hold down screws. In the upper part of frame (1) are arranged a main pole piece (3) having a polar face (3^a) and a second pole piece (4) having a polar face 50 (4^a). The pole pieces (2), (3) and (4) are embedded and secured in the integral frame (1) and made a unitary part thereof by being placed in the die or mold when the frame is cast, the parts being formed so that

the pole pieces and the integral frame structure have a secure interlocking engagement after the metal of the frame has solidified. 55

The pole piece (3) comprises a lower part (3^b), which is partially embedded in the non-magnetic metal, and an upwardly extending core part (3^c). The pole piece (4) preferably is partially embedded throughout its length in the wall (1^e) of the non-magnetic frame. 60

The bottom pole piece (2) is preferably 65 made of cast iron but I prefer to make the pole pieces (3) and (4) of laminated soft iron. The core extension (3^c) of the pole piece (3) is preferably turned down to the cylindrical form as indicated in Fig. 5. 70

The high tension generating winding (5) is removably mounted on the core extension 75 (3^c), said winding being in the form of a circular coil adapted to slip over the upper end of said core extension. The winding comprises a primary section (5^a) and a secondary section (5^b). 80

(6) is a magnetic member detachably mounted on the tops of the core extension (3^c), the pole piece (4) and the end and side walls of the frame (1). The member (6) may be formed in a single piece as shown or may be laminated. If desired, a plate (7) of magnetic material may be interposed between the magnetic member (6) and the core (3^c) and the pole piece (4), its object being to increase the effective area of contact between these parts and the area of the iron path between the magnets and the pole piece (4). As shown the plate (7) is 90 formed with an aperture to fit over the end of the core (3^c). 85

(8, 8) are L-shaped permanent magnets having their upper ends engaging the top of the magnetic member (6) and their lower ends engaging the side of the bottom pole piece (2), the engagement between the magnets and said parts (6) and (2) being on plane surfaces at right angles to each other. 95

A sheet metal cover plate (9) is secured to the base of the stator structure by screws (10, 10) and serves to hold the member (6) and magnet (8) in operative position. 100

The stator structure is formed or bored out to receive an inductor rotor designated 105 in its entirety by the numeral (11). Said rotor comprises the shaft (12) and the laminated flux distributing section (13)

mounted thereon. The shaft has its drive end mounted in an anti-friction bearing (14) in the end wall (1^a) of the stator frame while its other end is mounted in a similar bearing (15) in a removable end plate (16) of the stator frame, said end plate being secured in the integral part of the frame by screws (17, 17) and screw stud (18).

On one end of the shaft (12) is mounted 10 a cam (19) which serves to operate the usual circuit breaker mechanism designated in its entirety by (20). The circuit breaker mechanism is enclosed by a removable case (21). A gear (22), keyed on the rotor 15 shaft (12), drives the gear (23) of the distributor mechanism which is designated in its entirety by (24). The distributor (24) may be of any suitable construction. As shown it comprises a tubular shaft (25) 20 on which the gear (23) is mounted, and a rotating member (26) fitted in the shaft (25) and caused to rotate therewith by the stud (27) which, as shown, is formed integral with one of the rivets which secure the gear 25 (23) to the shaft (25). A bearing bushing (28) is preferably provided for the shaft (25). A radially extending metal arm (29) is connected at its inner end to a stem (30) which in turn is electrically connected 30 through spring pressed brushes (31) and (32), to the high tension terminal (33) of the generating winding (5). The brush (32) is mounted as shown in a block (34) of suitable insulating material said block being 35 secured by screws (not shown) to the end plate (1^a) of the stator frame.

The radially extending conductor (29), in operation, successively engages spring 40 pressed terminal brushes (35) mounted in the usual manner in the removable distributor cover (36). Spring clips (37, 37) serve to secure the distributor cover in place. The die-cast stator frame is formed with a chamber (38) which serves to house a safety 45 spark gap (39), said spark gap comprising an electrode (39^a) electrically connected to the high tension terminal of the winding (5) and an electrode (39^b) adjustably mounted in the said wall (1^a) of the stator frame. 50 (40) is a condenser which is conveniently mounted on the said wall (1^a) of the said frame.

The primary and secondary sections of 55 the generating winding, the condenser and the circuit breaker are connected in the usual manner which is well understood and which I have therefore not illustrated.

In the manufacture of my improved 60 generator, the bottom pole piece (2) is cast as nearly as may be to the final form, and the laminæ for the pole pieces (3) and (4) are stamped out approximately to the form shown in Fig. 2 and are then riveted together as indicated. After the pole piece 65 (3) has been riveted it is placed in a lathe

and the core extension (3^c) turned down to cylindrical form. The pole pieces (2), (3) and (4) are then ready to be placed in the mold, preferably a permanent mold or die, in which the non-magnetic stator frame is 70 cast. The composite frame structure thus secured is then machined as a unit, the magnetic inserts being machined off simultaneously with the adjacent parts of the non-magnetic frame structure. After the frame 75 has been machined off the bearing bushing (28) is forced in, the insulation block (34) is secured in position, the spark gap electrode (39^b) is inserted and the generating 80 coil (5) as a unit is slipped over the upper end of the core (3^c) with its high tension terminal (33) engaging the brush (32) and its spark gap electrode (39^a) opposite the electrode (39^b). Then the magnetic member 85 (7) (if used) is placed in position over the upper end of the core (3^c), the magnetic member (6), suitably machined, is placed in position, the condenser (40) is secured in position, and the permanent magnets are 90 applied as shown in Fig. 2. The cover part (9) is then put on and secured by screws 95 (10) thus effectively securing the parts (6) and (7) and the magnets (8) in position. It will be observed that the bottom pole structure consists essentially of the pole 100 piece (2), while the upper pole structure includes the pole piece (3) and the core (3^c), the pole piece (4), the magnetic member (6) and the part (7), if the latter is used.

The manner of assembling the rotor, 105 breaker and distributor parts and of making the electrical connections will be understood from the foregoing description.

In the operation of the generator, with the 110 rotor turning in the direction indicated by the arrow in Fig. 2, it will be seen that the flux distributor (13) causes the flux of the 115 magnets to pass first through the core (3^c) and its surrounding generating winding (5) and then through the pole piece (4) and outside of the generating winding, the pole 120 piece (4) constituting a magnetic by-pass for the flux. The breaker mechanism is timed so that the primary circuit of the generating winding is opened approximately when the decrease of flux through the core (3^c) is at its maximum, with the consequent generation of a high tension current in the secondary circuit, said currents being conducted through the distributor mechanism in the well known manner as the cycle of operations is repeated.

From the foregoing description those 125 skilled in the art will readily appreciate the advantages of the features characterizing my improved generator. The L-shaped magnets are of adequate length and yet they are more easily bent to form and more readily machined and fitted to the frame than are U-shaped magnets, for example. Thus 130

in grinding the sides of the magnets at their ends where they engage the top pole structure and the bottom pole piece it is only necessary that the surfaces be ground at right angles to each other, whereas in the case of U-shaped magnets it is necessary that the surfaces be ground parallel to each other and also to given dimensions. This feature of my invention reduces the cost of production.

Again, by forming the top pole pieces (3) and (4) separately, it is possible to turn the core extension (3^c) to cylindrical form, thus making possible the use of a round generating coil which can be produced at materially lower cost than a rectangular coil. Also the separate formation of the pole pieces (3) and (4) results in a minimum waste of metal in stamping the laminae.

Obviously the unit frame structure with cast-in pole pieces results in easier and less machine work with consequent reduction of the cost of production.

The size of my improved generator is small in proportion to its capacity because the L-shaped magnets make it possible to reduce the height of the machine in comparison with prior forms of inductor generators using straight magnets; and this reduction of size is further made possible by the use of the round generating coil which is more efficient than coils of rectangular form. The higher efficiency of the round generating coil arises from the fact that for a given flux path area the circular winding gives the shortest mean length of turn for the winding with a consequent minimum resistance, and from the further fact that at low generator speeds the heat of the spark or the length of gap the spark will jump varies inversely as the resistance of the primary winding, other conditions remaining unchanged. Furthermore, by keeping the length of the mean turn of the winding low a smaller winding conductor can be used without exceeding a given resistance, so that the mean distance of the coil turns from the core and, consequently, the flux leakage are minimized. Those familiar with the design problems peculiar to the inductor type of magnetos will appreciate the importance of reducing the dimensions of the winding to a minimum, the problem of finding adequate space for the stationary winding and for a distributor bearing of adequate length within the dimensions permissible, being a difficult one.

Again, in the construction illustrated, a material reduction in weight is effected by reason of the reduced size, the attachment of pole pieces by casting to the unit frame structure, and by the use of aluminum for the frame.

It is clear from the foregoing description that the parts of my improved generator can

readily be assembled and disassembled and it need only be added that the generating coil and associated parts can be disassembled without disturbing the rotor and its associated parts, a feature which constitutes a marked difference from the prior generators.

It will be noted that while the core (3^c) and the pole piece (4) must be made separate to permit the turning of the core to cylindrical form, it is not necessary for this purpose that the core be made integral with the pole piece (3). Indeed it is obvious that the upper pole structure can for this purpose be formed and arranged in relation to each other in various ways without sacrificing the advantages incident to the machining of the pole pieces as a unitary part of the frame structure, the cylindrical turning of the core, and the disassembly of the coil without dismounting the rotor. And in general, it will be understood that the construction shown and described is presented for purposes of illustration and explanation and that my improvements in many respects can be embodied in different constructions, the scope of the invention being indicated by the appended claims.

What I claim is:

1. In an ignition generator, the combination of a stator comprising pole structures of opposite polarity, an L-shaped permanent magnet having engagement at its respective ends with the said opposite pole structures on plane surfaces at right angles to each other, a magnetic rotor disposed between the stator poles, and a generating winding in inductive relation to the magnetic circuit through the stator and rotor.

2. In an ignition generator, the combination of a stator comprising pole structures of opposite polarity, an L-shaped permanent magnet having engagement at its respective ends with the said opposite pole structures on plane surfaces at right angles to each other, a generating winding on one of the stator poles, and an inductor rotor disposed between the stator poles.

3. In an ignition generator, the combination of a stator comprising pole structures of opposite polarity, one of said pole structures having a main pole and a by-pass, a generating winding on said main pole, an L-shaped permanent magnet having engagement at its respective ends with the said opposite pole structures on plane surfaces at right angles to each other, and an inductor rotor disposed between the stator poles adapted to distribute the magnetic flux alternately through the said main pole and the by-pass.

4. In an ignition generator, the combination of a stator comprising pole structures of opposite polarity, one of said pole structures having a cylindrical pole, a circular

generating coil fitted to said cylindrical pole, an L-shaped permanent magnet having engagement at its respective ends with said opposite pole structures on plane surfaces at 5 right angles to each other, and an inductor rotor disposed between the poles of opposite polarity.

5. In an ignition generator, the combination of an integrally cast non-magnetic 10 frame structure, a magnetic pole piece of one polarity embedded and secured in the bottom of said frame, a magnetic pole structure of the opposite polarity in the upper part of the frame, said pole structure comprising 15 a pair of pole pieces embedded and secured in said frame and a magnetic member detachably engaging said pole piece, a generating winding in inductive relation to one of said pair of pole pieces, an L-shaped 20 permanent magnet having one end engaging the bottom pole piece and its other end engaging said magnetic member, and a rotor disposed between the pole pieces of opposite polarity and adapted by its rotation to vary 25 the flux through the said winding.

6. In an ignition generator, the combination of an integrally cast non-magnetic frame structure, a magnetic pole piece of one polarity embedded and secured in the bottom 30 of the frame, a magnetic pole structure of the opposite polarity in the upper part of the frame, said pole structure comprising a main pole piece having its bottom part embedded and secured in the frame and provided 35 with a projecting core part adapted to receive a generating coil over its upper end and a second pole piece embedded and secured in the frame and adapted to constitute a by-pass around the main pole piece, 40 a generating winding on the said core part of the main pole piece, an L-shaped permanent magnet having one end joined to the bottom pole piece and its other end magnetically joined to the upper ends of said 45 main pole piece and by-pass, and an inductor rotor mounted between the opposite pole pieces.

7. In an ignition generator, the combi-

nation of an integrally cast non-magnetic frame structure, a magnetic pole piece of one 50 polarity embedded and secured in the bottom of the frame, a magnetic pole structure of the opposite polarity in the upper part of the frame, said pole structure comprising a main pole piece having its bottom part embedded and secured in the said frame and provided with a projecting core part adapted 55 to receive a generating coil over its upper end and a second pole piece embedded and secured in the frame and adapted to constitute a by-pass around the main pole piece and a magnetic member detachably engaging 60 said pole pieces, a generating coil on the said core part of the main pole piece, an L-shaped permanent magnet having one end joined to the bottom pole piece and its other end joined to the said detachable magnetic member, and an inductor rotor mounted between the opposite pole pieces.

8. In an ignition generator, the combination of an integrally cast non-magnetic frame structure, a magnetic pole piece of one polarity embedded and secured in the bottom 70 of the frame, a magnetic pole structure of the opposite polarity in the upper part of the frame, said pole structure comprising a main pole piece having its bottom part embedded and secured in the said frame and provided with a projecting cylindrical core 75 part adapted to receive a round generating coil over its upper end and a second pole piece embedded and secured in the frame and adapted to constitute a by-pass around the main pole piece and a magnetic member detachably engaging 80 said two pole pieces, a round generating coil on the said core part of the main pole piece, an L-shaped permanent magnet having one end joined to the bottom pole piece and its other end joined to the said detachable magnetic member, and an inductor rotor mounted between the 85 opposite pole pieces.

In testimony whereof, I hereunto affix my signature.

CHARLES H. TOWER.
